UNITED STATES PATENT OFFICE.

CONSTANTINE SAVITSKY, OF DENVER, COLORADO.

DICTIONARY-KEY.

1,353,615.

Specification of Letters Patent. Patented Sept. 21, 1920.

Application filed June 15, 1920. Serial No. 389,223.

To all whom it may concern:

Be it known that I, CONSTANTINE SAVITSKY, formerly a citizen of Russia, (having declared my intention of becoming a citizen of the United States,) residing in the city and county of Denver and State of Colorado, have invented certain new and useful Improvements in Dictionary-Keys; and I do declare the following to be a full, clear, and 10 exact description of the invention, such as will enable others skilled in the art to which it appertains to make and use the same, reference being had to the accompanying drawings, and to the characters of reference 15 marked thereon, which form a part of this specification.

The object of this invention is to provide a key for use with dictionaries which will facilitate the finding of words, particularly when using foreign-language 20 dictionaries.

The device is designed more particularly for the use of people with little education, who find the use of dictionaries difficult.

25 Briefly, the invention comprises a key provided with a master page for each letter of the alphabet, each master page being followed by a plurality of key pages. The master page classifies all of the words under the given letter under a few main heads, and further indicates where the different classifications will be found on the key pages immediately following. Each key page carries the numbers of several dictionary pages, 30 the guide words which are found at the top of each dictionary page being used in connection with the page numbers, and several of the main roots found in the respective columns of the dictionary pages also 35 being given.

In the drawings:

Figure 1 shows a master page.

Fig. 2 indicates a key page which in use is approximately the size of the master 40 pages.

Fig. 3 indicates a dictionary page; and

Fig. 4 shows a stamped diagram to be used in connection with the key.

Each master page 10 carries one of the 50 letters of the alphabet on a projecting tab in a well-known manner. The page is provided with a plurality of main classifications 12, which are divided under the vowels and also under other commonly-occurring letters. Thus the words under C may 55 be divided under Ca, Ce, Ch, Ci, Cl, Co, Cr, Cu and Cy. Each of the divisions 12 also carries a notation at 14 of the numbers of the key pages 15 under the given master page to which the specific division refers. 60 Where the division is rather large, it may be further subdivided, as shown under Co, where the various main roots found on each page are given. At the left of each division 12 there is shown at 16 the number 65 of words which are found in the dictionary under the specific division. For instance, under Ca there are 1,003 words, these words being numbered consecutively in the dictionary. Under Co there are 2,145 words. 70 At 18 the numbers of the dictionary pages under which the given division is found are indicated; thus the words under Ca are found in pages 141 to 165 of the dictionary, and under Co the words are found from 75 page 196 to page 254.

Each key page 15 is provided with two columns, which represent the two columns of the dictionary page D. Each of the columns carries the respective dictionary page 80 number, as indicated at 20, and at the left carries the guide letters 22 found on the left of the dictionary page, and at the right the guide letters 24 found at the right of the dictionary page. For convenience in finding a given root, the main roots found in each column of the given dictionary page are also shown under the proper page number 85 20, and in the proper column, as indicated at 25. 90

As above indicated, the words under each main division in the dictionary are numbered consecutively, these numbers being indicated in Fig. 3 at 26.

In using the key, the student turns to the 95 master key page 10 for the given letter. Assume that the word to be found is "Comb." He looks down the main divisions 12 until he finds Co. Under this he will find the root Com to be on pages 11, 12 and 13. He turns 100 to key page 11 under master page C, and finds "Comb" at the bottom of the page, this being found in connection with the dictionary page number 206. He turns to page 206 of the dictionary and finds the word, 105 which is numbered 419. To facilitate this work, especially where the student may wish to refer to the same word several times in mastering a given passage, a diagram is to be used which is preferably stamped on a 110 sheet of paper by means of a rubber stamp. This diagram is indicated at 30 in Fig. 4.

It contains a space 118 in which will be placed the numerals found at position 18 on the master page, which indicate the dictionary pages of the main division Co. A space, 112, is provided in which the numbers of the key pages 15 are to be placed, which indicate said main divisions. Where the main division is small, these will be the numbers indicated at 14; where the main division is large, the numbers will be the appropriate ones found in greater detail, as under Co, where the root Com is to be found on key pages 11, 12 and 13. Thus, for the word Comb the space 112 will carry the numerals 11—13. Space 120 is provided to receive the page number 20 when found on the respective key page 15, which, in the present instance, is 206. On the lower line of the diagram, space 126 is provided in which to place the dictionary number of the particular word, this being 419 for the word Comb. Alongside space 126 there is provided space 220 for the purpose of placing the dictionary page number in close proximity to 25 the word number. The word being found is written in space 32 and the foreign equivalent or the definition, as the case may be, is written in space 34. Where foreign dictionaries are used, which are provided in 30 two parts, as is frequently the case, a space 35 may be provided in order to indicate part 1 or part 2, as the case may be. Thus, by using this diagram, the word may be referred to as frequently as desired in case it 35 is necessary to look up different shades of meaning, the page number of the dictionary being given, and the word number also being given.

It is not to be understood that this device 40 will save any great amount of time in the use of a dictionary, either foreign or domestic, by a well educated person, but where the person has very little education and finds the use of the dictionary tedious, it will save 45 much time, particularly where it may be necessary to refer frequently to the same word for different shades of meaning.

I claim:

1. In a dictionary key, a master page for 50 each letter of the alphabet, a series of main word divisions for each letter indicated on

the respective master pages, a plurality of key pages associated with each master sheet, indicia in each of said word divisions referring to certain of said key pages, each key page containing a series of word roots, and page numbers associated with said roots referring to pages in a dictionary. 55

2. In combination, a dictionary and a dictionary key comprising a master page for each letter of the alphabet, a series of main 60 word divisions on each master page, the words in the dictionary of each word division indicated by the respective master sheets as being numbered consecutively, each of said divisions on the master sheets indicating the number of pages in the dictionary covering the respective division and the number of words in said division, a plurality of key pages associated with each master sheet, indicia in each of said word divisions 65 indicating key pages covering the respective division, each key page containing a series of word roots and the dictionary page numbers associated with the respective roots. 70

3. In combination a dictionary and a dictionary key comprising a master page for each letter of the alphabet, a series of main word divisions on each master page, and a plurality of key pages associated with each master page, each word division having in- 75 dicia indicating the key pages covering said division, each key page carrying a plurality of page numbers indicating pages in said dictionary, and word roots associated with said numbers and indicating the roots of the 80 words found on the respective dictionary pages. 85

4. In combination, a dictionary, and a dictionary key comprising a master page for each letter of the alphabet, each master page 90 having a series of main word divisions, a series of key pages under each master page, indicia in each main word division indicating the key pages covering said main division, each key page having word sub-divisions and indicia associated with said sub-divisions indicating dictionary pages on 95 which words of said sub-divisions are found.

In testimony whereof I affix my signature.

CONSTANTINE SAVITSKY.
